DESIGN FOR A CABINET FOR LIQUID FUEL HEATERS

William T. Bradbury, Hatboro, Pa., assignor to
Florence Stove Company, Gardner, Mass., a
corporation of Massachusetts

Application May 8, 1935, Serial No. 56,731

Term of patent 7 years

To all whom it may concern:

Be it known that I, William T. Bradbury, a citizen of the United States, residing at Hatboro, in the county of Montgomery and State of Pennsylvania, have invented a new, original, and ornamental Design for a Cabinet for Liquid Fuel Heaters, of which the following is a specification, reference being had to the accompanying drawing, forming part thereof.

The figure is a perspective view showing the front, side, and top of the cabinet embodying the features of the novel design, the side not shown being identical to that shown in the drawing.

I claim:

The ornamental design for a cabinet for liquid fuel heaters, substantially as shown and described.

WILLIAM T. BRADBURY.
